R. M. CRAIG

UMBRELLA

Filed Dec. 8, 1925

INVENTOR:
ROBERT MEADE CRAIG,
R. M. Craig

Patented July 27, 1926.

UNITED STATES PATENT OFFICE.

ROBERT MEADE CRAIG, OF WILKINSBURG, PENNSYLVANIA.

UMBRELLA.

Application filed December 8, 1925. Serial No. 74,004.

My invention relates to umbrellas of the type wherein the handle stick of the umbrella is in concentric relation with the cover, at the thimble to which the ribs are pivoted, but is adapted to extend in eccentric relation with the axis of the cover, at the other end; so that when the umbrella is raised, the cover may be held in a horizontal plane with the center over the head of the user, by grasping said handle at one side of the user.

In the form of my invention hereinafter described, the braces from the ribs to the runner are of unequal length, in correspondence with the degree of eccentricity of the handle with respect to the umbrella axis when the cover is raised. If such braces were pivoted to the runner, in the ordinary manner, the umbrella could not be collapsed to present the ribs in parallel relation with the stick. Therefore, an essential feature of my invention is the provision of pivot slots in the runner, parallel with the axis of the stick, wherein the pivoted ends of the braces may slide to such an extent as to permit the ribs to be folded parallel with the stick. Moreover, as it is advantageous to enable the user to determine the direction of the plane in which the stick is eccentric with respect to the cover, without looking at the latter; a convenient adjunct of my invention is the combination, with such a slotted runner, of a stick of flattened cross section, having its major transverse axis in the plane of eccentricity of the cover.

Furthermore, my invention provides means to permit the insertion and removal of any rib or brace without the services of a skilled operator, by making the pivot ends of the ribs and braces T-form so that they may be released by turning them at right angles to their normal position and by pivotally connecting each rib with its brace by means of a flexible pivot pin which may be straightened out and withdrawn, so that when thus released from each other, the ribs and braces may be separately turned to disengage their pivot ends from the thimble and runner.

My invention includes the various novel features of construction and arrangement hereinafter more definitely specified.

In said drawings; Fig. I is an elevation of a raised umbrella conveniently embodying my invention.

Fig. II is an elevation of said umbrella collapsed with its ribs parallel with its stick and handle.

Fig. III is a fragmentary perspective view of one of the ribs and its brace indicated in Fig. I.

Fig. IV is a perspective view of the flexible pivot pin indicated in Fig. III, but removed from its connection of the rib and brace.

Fig. V is a longitudinal sectional view of the runner indicated in Fig. I, with fragments of the stick and braces connected therewith.

Fig. VI is a fragmentary transverse sectional view of the runner and stick with braces indicated in dotted lines.

In said figures; the ribs 1 and the braces 2 are normally connected by pivot pins 3 which may be bent and removed. The pivot ends of the rib and brace, shown respectively at 4 and 5 in Fig. III are T-shaped and respectively pivotally engaged in sockets in the thimble 6 and runner 7 from which they cannot escape when in normal position but from which they may be removed by rotation to a position at right angles to their normal position. That is to say, upon removing any pivot pin 3, both the rib 1 and the brace 2 which it normally connects may be thus turned and removed from the umbrella.

As best shown in Fig. I; the braces 2 upon one side are shorter than upon the other side of the umbrella frame so that the umbrella handle 9 extends obliquely to one side of the axis 10 of the umbrella when the latter is opened, and, consequently, the umbrella cover 11 may be held in horizontal position with the handle 9 extending to either hand of the user.

In order to permit the umbrella to collapse with said handle 9 in parallel symmetrical relation with said ribs 1; the umbrella runner 12 has slots 13 of different lengths in it, up which the pivot ends for the braces 2 slide when the runner is lowered to bring the ribs 1 together. However, said runner 12 has the loose ring 15 in it which frictionally engages the handle stick 16 and rests upon the top of the pivot ends of the braces when the umbrella is raised; said ring being shifted back and forth on said stick by the manual movement of said runner.

As best shown in Fig. VI; said stick 16

is conveniently formed as a primarily cylindrical tube which is flattened to an elliptical configuration with its major transverse axis held in the plane in which the handle is 5 eccentric, by the engagement of said stick in a correspondingly elliptical tubular portion 17 of the runner; so that the user can determine, in the dark, the eccentric location of the umbrella frame and cover with respect to its handle.

Although I prefer to construct and arrange an umbrella with all of the features above described; it is to be understood that the specific pivotal construction and arrangement of the rib and brace shown in Fig. III is not essential to the combination of the braces of different lengths with the runner having slots permitting longitudinal movement of the pivot ends of the braces 15 therein, for the purpose of permitting collapse of the umbrella with its ribs parallel with its stick and handle. Moreover, although the formation of the handle stick and runner of flattened form is advantageous, as above noted, such construction is 20 not essential to the utility of the slotted runner and its appurtenant braces.

Therefore, I do not desire to limit myself to the precise details of construction and arrangement herein set forth, as it is obvious 30 that various modifications may be made therein without departing from the essential features of my invention, as defined in the appended claims.

35 I claim:—

1. In an umbrella, the combination with a metal tubular handle stick of flattened cross section; of a thimble rigidly connected with said stick; a circular series of ribs of equal 40 length pivotally connected with said thimble; a circular series of braces pivotally connected with said ribs at equal distances from the pivotal connections of said ribs with said thimble; said braces being of unequal length; the longest and shortest braces being diametrically opposed in the plane of the major axis of the elliptical configuration of said stick; a tubular runner on said stick 45 having a portion of elliptical cross section closely fitting said stick, and having a portion in spaced relation with said stick with a circular series of slots 50 therein extending parallel with the stick and of respectively different lengths corresponding with the different lengths of said braces; said braces having their ends remote from said ribs respectively pivotally connected in said runner slots, and adapted to slide longitudinally in said slots; a friction ring encircling said stick, within said runner, and adapted to bear upon the pivot ends of said braces in said runner and shift them to one end of said slots, when the umbrella is raised; whereby said stick is held 55 in oblique relation with the axis of the umbrella, with the handle presented in eccentric relation with the axis of the umbrella, when the umbrella is raised, and said ribs and braces may be folded parallel with said stick, in symmetrical relation with the umbrella axis when the umbrella is closed.

- 55 2. In an umbrella, the combination with a handle stick; of a thimble rigidly connected with said stick; a circular series of ribs pivotally connected with said thimble; a circular series of braces pivotally connected with said ribs; said braces being of unequal length; the longest and shortest braces being diametrically opposed; a tubular runner on said stick, having a cylindrical portion in spaced relation with said stick with a circular series of slots extending parallel with the stick and of respectively different lengths

brella, with the handle presented in eccentric relation with the axis of the umbrella, when the umbrella is raised; and said ribs and braces may be folded parallel with said stick, in symmetrical relation with the umbrella axis when the umbrella is closed; the ends of said ribs pivotally connected with said thimble, and the ends of said braces pivotally connected with said runner being T-shaped and the pivotal connections between said ribs and braces comprising removable flexible pins; whereby, upon removal of any such pivot pin, the rib and brace which it normally connects may be independently turned through an angle of ninety degrees and removed from its pivotal connections, respectively with said thimble and with said runner.

2. In an umbrella, the combination with a metal tubular handle stick of flattened cross section; of a thimble rigidly connected with said stick; a circular series of ribs pivotally connected with said thimble; a circular series of braces pivotally connected with said ribs at equal distances from the pivotal connections of said ribs with said thimble; said braces being of unequal length; the longest and shortest braces being diametrically opposed in the plane of the major transverse axis of the stick; a tubular runner on said stick having a portion of flattened cross section closely fitting said stick, and having a portion in spaced relation with said stick with a circular series of slots therein extending parallel with the stick and of respectively different lengths corresponding with the different lengths of said braces; said braces having their ends remote from said ribs respectively pivotally connected in said runner slots, and adapted to slide longitudinally in said slots; a friction ring encircling said stick, within said runner, and adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised, and said ribs and braces may be folded parallel with said stick, in symmetrical relation with the umbrella axis when the umbrella is closed.

3. In an umbrella, the combination with a handle stick; of a thimble rigidly connected with said stick; a circular series of ribs pivotally connected with said thimble; a circular series of braces pivotally connected with said ribs; said braces being of unequal length; the longest and shortest braces being diametrically opposed; a tubular runner on said stick, having a cylindrical portion in spaced relation with said stick with a circular series of slots extending parallel with the stick and of respectively different lengths

- corresponding with the different lengths of said braces; said braces having their ends remote from said ribs respectively pivotally connected in said runner slots, and adapted to slide longitudinally in said slots; and means, within said runner, adapted to bear upon the pivot ends of said braces in said runner and shift them to the ends of said slots, when the umbrella is raised; whereby 10 said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
4. In an umbrella, the combination with a handle stick; of a thimble rigidly connected with said stick; a circular series of ribs pivotally connected with said thimble; a circular series of braces pivotally connected with said ribs; said braces being of unequal length; the longest and shortest braces being diametrically opposed; a tubular runner on said stick, having a cylindrical portion in spaced relation with said stick with a circular series of slots extending parallel with the stick and of respectively different lengths 20 corresponding with the different lengths of said braces; said braces having their ends remote from said ribs respectively pivotally connected in said runner slots, and adapted to slide longitudinally in said slots; whereby 25 said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
5. In an umbrella, the combination with a handle stick; of a thimble rigidly connected with said stick; a circular series of ribs pivotally connected with said thimble; a circular series of braces pivotally connected with said ribs; said braces being of unequal length; the longest and shortest braces being diametrically opposed; a tubular runner on said stick having a circular series of slots extending longitudinally therein; said braces having their ends remote from said ribs respectively pivotally 30 connected in said runner slots, and adapted to slide longitudinally in said slots; a friction ring encircling said stick, within said runner, and adapted to bear upon the pivot ends of said braces in said runner and shift them to one end of 35 said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
6. In an umbrella, the combination with a handle stick; of a thimble rigidly connected with said stick; a circular series of ribs pivotally connected with said thimble; a circular series of braces pivotally connected with said ribs; said braces being of unequal length; the longest and shortest braces being diametrically opposed; a tubular runner on said stick having a circular series of slots extending longitudinally therein; said braces having their ends remote from said ribs respectively pivotally 40 connected in said runner slots, and adapted to slide longitudinally in said slots; means within said runner; and adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
7. In an umbrella, the combination with a handle stick; of a thimble rigidly connected with said stick; a circular series of ribs pivotally connected with said thimble; a circular series of braces pivotally connected with said ribs; said braces being of unequal length; the longest and shortest braces being diametrically opposed; a tubular runner on said stick having a circular series of slots extending longitudinally therein; said braces having their ends remote from said ribs respectively pivotally 45 connected in said runner slots, and adapted to slide longitudinally in said slots; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
8. In an umbrella, the combination with a metal tubular handle stick of elliptical cross section; of a thimble rigidly connected with said stick; a circular series of ribs of equal length pivotally connected with said thimble; a circular series of braces pivotally connected with said ribs at equal distances from the pivotal connections of said ribs with said thimble; said braces being of unequal length; the longest and shortest braces being diametrically opposed in the plane of the major axis of the elliptical configuration of the stick.
9. In an umbrella, the combination with a metal tubular handle stick of elliptical 50

- cross section; of a thimble rigidly connected with said stick; a circular series of ribs of equal length pivotally connected with said thimble; a circular series of braces pivotally connected with said ribs; said braces being of unequal length; the longest and shortest braces being diametrically opposed in the plane of the major axis of the elliptical configuration of the stick.
10. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; the longest and shortest braces being diametrically opposed in the plane of the major axis of the elliptical configuration of the stick.
15. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; the longest and shortest braces being diametrically opposed in the plane of the major axis of the elliptical configuration of the stick.
20. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; the longest and shortest braces being diametrically opposed in the plane of the major axis of the elliptical configuration of the stick.
25. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; a tubular runner on said stick having a circular series of slots extending parallel with the stick and of respectively different lengths corresponding with the different lengths of said braces; said braces having their ends remote from said ribs respectively pivotally connected in said runner slots, and adapted to slide longitudinally in said slots; and means adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
30. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; a tubular runner on said stick having a circular series of slots extending parallel with the stick and of respectively different lengths corresponding with the different lengths of said braces; said braces having their ends remote from said ribs respectively pivotally connected in said runner slots, and adapted to slide longitudinally in said slots; and means adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
35. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; a tubular runner on said stick having a circular series of slots extending parallel with the stick and of respectively different lengths corresponding with the different lengths of said braces; said braces having their ends remote from said ribs respectively pivotally connected in said runner slots, and adapted to slide longitudinally in said slots; and means adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.
40. In an umbrella, the combination with a metal tubular handle stick of elliptical cross section; of a thimble rigidly connected with said stick; a circular series of ribs pivotally connected with said thimble; a circular series of braces pivotally connected with said ribs; said braces being of unequal length; a tubular runner on said stick having a circular series of slots extending parallel with the stick and of respectively different lengths corresponding with the different lengths of said braces; said braces having their ends remote from said ribs respectively pivotally connected in said runner slots, and adapted to slide longitudinally in said slots; and means adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.

the axis of the umbrella, when the umbrella is raised; and said ribs and braces may be folded parallel with said stick, in symmetrical relation with the umbrella axis when the umbrella is closed.

12. In an umbrella, the combination with a handle stick; of a thimble rigidly connected with said stick; a circular series of ribs pivotally connected with said thimble; a circular series of braces pivotally connected with said ribs; said braces being of unequal length; a tubular runner on said stick having a circular series of slots extending parallel with the stick; said braces having their ends remote from said ribs respectively pivotally connected in said runner slots, and adapted to slide longitudinally in said slots; and means adapted to bear upon the pivot ends of said braces in said runner and shift them to one end of said slots, when the umbrella is raised; whereby said stick is held in oblique relation with the axis of the umbrella, with the handle presented in eccentric relation with the axis of the umbrella, when the umbrella is raised; and said ribs and braces may be folded parallel with said stick, in symmetrical relation with the umbrella axis when the umbrella is closed.

13. An umbrella handle stick comprising a metal tube which is of cylindrical configuration for a portion of its length and flattened to substantially elliptical configuration at another portion of its length; whereby the relative position of rotation of an umbrella may be tactually determined by the user.

In testimony whereof, I have hereunto signed my name at Wilkinsburg, Pennsylvania, this 21st day of November, 1925.

ROBERT MEADE CRAIG.
